UNITED STATES PATENT OFFICE.

ALFRED GOLDSMITH, OF NEW YORK, N. Y., ASSIGNOR TO L. D. BLOCH & COMPANY, OF NEW YORK, N. Y., A CORPORATION OF NEW YORK.

DESIGN FOR A NUT-BOWL.

49,486.

Specification for Design.

Patented Aug. 8, 1916.

Application filed May 29, 1916. Serial No. 100,697. Term of patent 7 years.

To all whom it may concern:

Be it known that I, ALFRED GOLDSMITH, a citizen of the United States, residing at New York city, in the county and State of New York, have invented a new, original, and ornamental Design for a Nut-Bowl, of which the following is a specification, reference being had to the accompanying drawings, forming a part thereof, and in which— Figure 1 is a perspective view and Fig.

2 is side elevation of a nut bowl embodying my design.

I claim:

The ornamental design for a nut bowl, as shown.

ALFRED GOLDSMITH.

Witnesses:

ARTHUR MARION,
CHAS. C. GILL.
